UNITED STATES PATENT OFFICE.

GEORGE C. THOMAS, OF WATERBURY, CONNECTICUT.

LAMP-FIXTURE.

SPECIFICATION forming part of Letters Patent No. 314,080, dated March 17, 1885.

Application filed October 6, 1884. (No model.)

To all whom it may concern:

Be it known that I, GEORGE C. THOMAS, of Waterbury, in the county of New Haven and State of Connecticut, have invented a new and 5 useful Improvement in Lamp-Fixtures, of which the following is a specification.

The object of my present improvement is to provide a very cheap yet novel lamp-fixture frame.

10 The improvement consists in a lamp-fixture frame made of a strip or strips of sheet metal curved edgewise in the direction of the length, and having perforations or cuttings at the outer edge.

15 In the accompanying drawings, Figure 1 is a partly-sectional side view of a lamp-fixture frame embodying my improvement. Fig. 2 is an edge view of the same. Fig. 3 is a partly-sectional side view of a lamp-fixture frame of modified form embodying my improvement; 20 and Fig. 4 is a bottom view or inverted plan of a lamp-fixture frame of modified form embodying the improvement.

25 Similar letters of reference designate corresponding parts in all the figures.

In Figs. 1 and 2 I have shown a lamp-fixture frame in which is a strip of sheet metal, *a*, bent edgewise and cut or perforated along the outer edge. The cutting or perforation 30 shown is made by indenting or embossing the sides near the outer edge and cutting it from the outer edge inward. Preferably I form the cuttings or perforations first, and then bend the strip in accordance with a process for 35 which I have already filed an application for Letters Patent.

The ends of the strip are cut so as to produce parallel edges, and rods or upright arms *b* are secured to them. These rods or arms 40 are made of metal. They may be split to embrace the ends of the strip and secured thereto

by rivets, solder, or other means. They are intended to have attached to their upper ends chains for suspending the frame.

A pull-piece or finial, *c*, will preferably be 45 fastened to the lower portion of the strip *a*. It may be made of metal. Preferably it will be split or bifurcated so as to embrace the strip *a*, and secured thereto by rivets, solder, or equivalent means.

50 The lamp-fixture frame shown in Fig. 3 has two strips of metal, *a* and *a'*, which are made like the strip *a* of the lamp-fixture frame first described, except that they are severally about half the length. They are joined at the pull-piece or finial *c* by rivets, solder, or other suitable means. In other respects the frame shown in Fig. 3 may be like the one shown in 55 Figs. 1 and 2.

The lamp-fixture frame shown in Fig. 4 is 60 like the one shown in Fig. 3, except that three strips, *a*, *a'*, and *a''*, like the strips *a* and *a'* shown in Fig. 3, are united by the pull-piece or finial *c*.

The pull-piece or finial *c* may extend above 65 the strips *a* *a'* *a''* shown in the several figures, to form a protuberance capable of entering a cavity in a lamp-reservoir. Instead of employing such a holder for a lamp-reservoir, I may attach a cup-shaped reservoir-holder to 70 the frame.

What I claim as my invention, and desire to 75 secure by Letters Patent, is—

As a new article of manufacture, a lamp-fixture frame made of a strip or strips of sheet metal curved edgewise in the direction of the length, and having cuttings or perforations at the outer edge, substantially as specified.

GEORGE C. THOMAS.
